UNITED STATES PATENT OFFICE.

JOHN EDWARD DAVIS, OF WASHINGTON, NEW JERSEY.

ORGAN.

SPECIFICATION forming part of Letters Patent No. 605,404, dated June 7, 1898.

Application filed October 16, 1897. Serial No. 655,413. (No model.)

To all whom it may concern:

Be it known that I, JOHN EDWARD DAVIS, of Washington, in the county of Warren and State of New Jersey, have invented certain new and useful Improvements in Organs, of which the following is a full, clear, and exact description.

The object of the invention is to provide certain new and useful improvements in organs and like wind instruments whereby a proper actuating of the swells, mutes, couplers, and like parts is obtained without binding and undue friction of the moving parts caused by sidewise motion and shrinkage in any form.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement as applied and with part broken out. Fig. 2 is a cross-section of the same on the line 2-2 of Fig. 1. Fig. 3 is a rear elevation of the same, and Fig. 4 is a perspective view of the lever.

Each of the stops A is fitted to slide in the usual bearings in the organ-casing B, and each stop is provided with a guide C for preventing the stop from turning and for limiting the inward and outward movement of the stops when pulled or pushed by the organist.

On each stop A, within the casing B, is arranged a pivot D, on which is hung a depending link E, guided in its lateral movement between the walls of a slot in the stop, as is plainly indicated in Figs. 1 and 2, the lower or free end of the said link being formed with a fork E', straddling the pin F' of a lever F, which constitutes the main portion of the improvement.

The lever F is made of a single piece of wire, with its pivot portion F² formed at one end with an arm F³, carrying at its free forward end the aforesaid pin F', said pin standing parallel to the pivot F². The other end of the pin is formed with an arm F⁴, extending downward and upward at right angles to the arm F³, with a bend F⁵ termi-

nating in the end F⁶, arranged to carry a block G, connected by a link H with a mute, swell, coupler, or other part I, as indicated in the drawings. The end F⁶, carrying the block G, is arranged in alinement with the link E and the stop A—that is, in the plane of movement of the lever F and the said stop—so that a central draft is obtained to insure a proper opening and closing of the mute, swell, coupler, or like parts and irrespective of shrinkage in the casing or other parts of the organ. It is understood that by the peculiar arrangement of the arms F³ F⁴ and the location of the bend F⁵ the above result is obtained.

The pivot portion F² of the lever F is set in a bearing B', formed longitudinally in one of the rear walls of the casing B, the said bearing being in the form of a slot closed by a strip B', as is plainly indicated in Figs. 2 and 3.

Now when the swell, mute, coupler, or the like is in a normal position then the stop A is in its innermost position, as indicated in full lines in Fig. 2, with the link E extending forward, as shown. When the stop A is pulled outward, the link E presses on the pin F' in a downward direction and imparts a swinging motion to the lever F, so that the arm F⁴ swings transversely in a rearward direction to pull on a link H and open the mute, swell, or coupler I, as indicated in dotted lines in Fig. 2. When the stop is pulled outward to its full extent, then the link E passes a central position, as indicated in dotted lines in Fig. 2, so that when the organist releases the knob of the stop the several parts remain locked in this position. When the organist pushes the knob of the stop inward, then the several parts return to their original position owing to the spring connected with the part to be actuated, the closing of the mutes or swells being gradual, as the link assumes its normal inclined position when the stop is pushed in.

Several connections between the stop and the part to be actuated are shown in the drawings, and one has been described, it being understood, however, that for making the connection between the lever and the part to be actuated various means besides the link H may be employed. For instance, as shown

in the drawings, the lever F for the stop A¹ has its block G connected by a link H' with a lever J, connected by a link J' with a swell J², and the stop A² has the block G of its lever F connected by a link K with a mute K', fulcrumed in the casing.

Now it will be seen that the lever F can be readily constructed and easily applied on an organ without requiring much fitting by 10 skilled workmen.

Having thus fully described my invention, I claim as new and desire to secure by Letters Patent—

1. An organ, provided with a lever formed 15 with a pivot portion, and arms extending therefrom and at angles to each other, one of said arms having a bent portion extending parallel and in alinement with said pivot portion and arranged for connection with the 20 actuating part, and the other arm being formed with a bend by which it is brought in line with the center of the pivot portion, said latter arm being arranged for connection with the part to be actuated, as set forth.
2. In an organ, the herein-described lever formed with a transversely-extending pivot portion held to rotate on its longitudinal axis 25 in a bearing in the organ, an arm extending from one end of said pivot portion and at an angle thereto, said arm having its end bent 30

parallel and in alinement with the pivot portion and by which it is connected with the actuating part, and a second arm extending from the opposite end of said pivot portion and at an angle thereto, said second arm being formed with a bend by which it is brought in line with the center of the pivot portion and being arranged for connection with the part to be actuated, as set forth. 35

3. In an organ, the combination with a 40 frame and a stop fitted in said frame and having a link pivoted thereon, of a lever formed of a single piece of wire bent to form a transverse pivot portion mounted to rotate on its longitudinal axis in a bearing in said frame 45 and having its center in line with said link, and two arms extending in opposite directions from the ends of said pivot portion and at an angle thereto, one of said arms being provided with a pin extending parallel with 50 said pivot portion and arranged for connection with said link, and the other arm having its end bent in line with the center of said pivot portion and arranged for connection with the part to be actuated, as set forth. 55

JOHN EDWARD DAVIS.
